(57) **CLAIM**

The ornamental design for pivot mount rail adaptor, as shown and described.

DESCRIPTION

FIG. 1 is an isometric view of the pivot mount rail adaptor of the present invention;

FIG. 2 is a front elevational view of the rail adaptor of FIG. 1;

FIG. 3 is a back elevational view of the rail adaptor of FIG. 1;

FIG. 4 is a left elevational view of the rail adaptor of FIG. 1;

FIG. 5 is a right elevational view of the rail adaptor of FIG. 1;

FIG. 6 is a top view of the rail adaptor of FIG. 1;

FIG. 7 is a bottom view of the rail adaptor of FIG. 1;

FIG. 8 is an isometric view of the pivot mount rail adaptor of the present invention;

FIG. 9 is a front elevational view of the rail adaptor of FIG. 8;

FIG. 10 is a back elevational view of the rail adaptor of FIG. 8;

FIG. 11 is a left side elevational view of the rail adaptor of FIG. 8;

FIG. 12 is a right side elevational view of the rail adaptor of FIG. 8;

FIG. 13 is a top view of the rail adaptor of FIG. 8; and,

FIG. 14 is a bottom view of the rail adaptor of FIG. 8.
